[57] CLAIM

The ornamental design for a combined wine and glass rack, as shown and described.

DESCRIPTION

FIG. 1 is a front view of a combined wine and glass rack showing my new design;

FIG. 2 is a left side view thereof;

FIG. 3 is a right side view thereof;

FIG. 4 is a top view thereof;

FIG. 5 is a bottom view thereof;

FIG. 6 is a rear view thereof;

FIG. 7 is a top perspective view thereof; and,

FIG. 8 is a top perspective view thereof, the broken lines representing wine bottles and glasses are for illustrative purposes only and form no part of the claimed design.
